LIFT TRUCK

Elmer S. Frost, Oakland, Calif.

Application June 4, 1934, Serial No. 723,012

3 Claims. (CL 254—2)

This invention relates to a truck designed primarily for lifting and moving stoves and other heavy articles, one of the objects being to provide a simple and compact structure utilizing 5 a novel form of hydraulic jack which can be operated easily for the purpose of lifting a load and for lowering the same.

A still further object is to provide a device of this character which permits the supported object to be rotated to any desired position while supported, there being a lock for preventing this rotation when desired.

With the foregoing and other objects in view which will appear as the description proceeds, 15 the invention consists of certain novel details of construction and combinations of parts herein-after more fully described and pointed out in the claims, it being understood that changes may be made in the construction and arrangement of parts without departing from the spirit 20 of the invention as claimed.

In the accompanying drawings the preferred form of the invention has been shown.

In said drawings

25 Figure 1 is a side elevation of the complete truck.

Figure 2 is a plan view thereof, a portion of the top being broken away.

Figure 3 is an enlarged section through the 30 jack.

Referring to the figures by characters of reference 1 designates a suitable base mounted on casters 2 or other supports whereby it can be moved readily from place to place.

35 Secured on the base, is the base block 3 of the back portion of the truck. This block has a large boss 4 extending upwardly therefrom into a tubular standard 5 to which it can be secured by means of screw threads as shown at 6.

A screw threaded recess 7 is formed in the boss 4 at the center thereof and secured therein is the lower end of a cylinder 8. Thus an annular compartment 9 is formed around the cylinder 8 and within standard 5 and constitutes a tubular reservoir. The top end of the reservoir is closed by a head 10 fastened to a ring 11 welded or otherwise joined to the top of the standard. This head is provided at its center 50 with a packing 12 while its margin is provided with notches 13 suitably spaced. Braces 14 are secured to the ring 11 and diverge downwardly from the upper portion of the standard 5 to the base 1 where they are securely fastened as 55 shown at 15. Obviously these braces cooperate

to hold the standard 5 fixedly in upstanding position relative to block 3 and base 1.

Formed within the block 3 at a point outside of the standard 5 is a threaded recess 16 in which is secured the lower end of the cylindrical casing 17 of a plunger 18 forming a force pump. This plunger is mounted for reciprocation within its casing and is adapted to be actuated by a hand lever 19 one end of which is pivotally mounted on a supporting bracket 20 while an intermediate portion is pivotally connected, as at 21', to the plunger 18.

Extending downwardly within block 3 from the recess 16 is a passage 21 intersected by an upper return passage 22 and a lower out-flow 15 passage 23. The out-flow passage 23 opens into the recess 1 as shown at 24 while the return passage 22 opens upwardly into the reservoir 9 as shown at 25.

Passage 22 has a valve seat 26. A check valve 20 preferably comprising a ball 27 engaged by a spring 28 is held normally against seat 26 so as to prevent the flow of fluid from casing 17 and passage 21 into reservoir 9.

Passage 21 is provided with a valve seat 29 25 normally engaged by a check valve which, in the structure shown, comprises a ball 30 held to its seat by a spring 31. Thus this valve will act to open under the pressure of fluid being forced into passage 21 from casing 17 but to 30 close under backward pressure from recess 1 and cylinder 8.

A bypass 32 connects the passages 22 and 23 and is normally closed by a valve 33. This valve has a long stem 34 extending outwardly from 35 the block 3 and provided with a handle, foot lever or the like shown at 35 whereby the valve can be turned readily to open or close the bypass.

A rotatable shank 36 is mounted to slide within the cylinder 8 and has its lower portion 40 enlarged as at 37 to form a piston. To the upper end of this shank is securely fastened the top 38 of the jack and to this top is pivotally connected a spring-pressed dog 39 adapted to be seated in any one of the notches 13 so as to hold the 45 shank 36 and top 38 against rotation. This dog is of sufficient length to remain in engagement with a notch while the shank 36 is being moved upwardly or downwardly as hereinafter explained.

50 It is to be understood that reservoir 9 is to be partly filled with a suitable fluid such as oil and, in order to prevent the creation of a vacuum within the reservoir, vent tubes 40 can be supported within the upper portion of the reservoir, 55

each of these tubes having openings 41 for permitting the flow of air into or out of the reservoir.

If it is desired to lift a stove or other heavy object, the truck is moved to position thereunder with the top 38 in its lowermost position. The lever 19 is then actuated to reciprocate plunger 18. During each upward stroke of the plunger oil will be sucked into the casing 17 by way of passage 22 at which time valve 21 will open and valve 30 will remain closed. During each downward stroke of the plunger, valve 21 will close and valve 30 will open. Thus the oil forced out of the casing 17 by the descending plunger will flow into passage 21 and thence to passage 23 from which it will enter cylinder 8 beneath piston 37 and cause the shank 36 and the load thereon to move upwardly. As valve 30 will prevent return flow of the liquid, the elevated parts will be held against movement downwardly when the pumping action is discontinued. The truck with the load thereon can then be moved to any point desired, it being understood that the dog 39 will prevent the load from turning. Thereafter the dog can be disengaged from the notched head and the top 37 rotated to bring the stove or other object into proper position to be lowered. By now opening valve 33 the liquid under the piston 37 will be free to flow through bypass 32 into passage 22 and thence back to the reservoir where it will be stored for further use. As the fluid thus escapes to the reservoir the load will be gently lowered into position and thereafter the truck can be withdrawn.

What is claimed is:

1. In a lift truck, a wheel supported base, an upstanding cylinder thereon, a piston slidably and rotatable in the cylinder and having a shank 40 extending upwardly from said cylinder, a load

engaging element at the top of the shank and rotatable with the shank and piston, means for elevating the piston and shank relative to the cylinder, an annular head on the cylinder, a member pivotally suspended from the load engaging element, said member being adapted to slidably engage the head during the sliding movement of the shank, said head having means for cooperating with said member for holding the shank and load engaging element against rotation relative to the cylinder after the rotation of said shank and element to certain predetermined positions. 5

2. A lift truck including a wheel supported base, a cylinder mounted thereon including a 15 cylinder and a shank slidably and rotatably mounted within and above the cylinder, an annular head on the cylinder, a load engaging element movable with the shank, and spring pressed means extending from the said element for slid- 20 ably engaging said head and for holding said element and shank against rotation after their rotation to any one of a series of predetermined positions.

3. A truck including a base, an upstanding 25 cylinder thereon, a slidable and rotatable shank guided and surrounded by the cylinder, a load-engaging element at the top of the shank adjustable angularly with the shank to any one of a plurality of predetermined positions, and co- 30 operating means on said element and the cylinder for holding said element against rotation after annular adjustment to a selected position without interfering with its reciprocation, said means including a head fixed to the cylinder 35 and having a series of notches in its periphery, and an elongated dog depending from the load-engaging element and slidably within one of the notches during the reciprocation of the shank.
